UNITED STATES PATENT OFFICE

CORNELIS F. M. VAN BERKEL, OF WASSENAAR, NETHERLANDS, ASSIGNOR TO U. S. SLICING MACHINE COMPANY, OF LA PORTE, INDIANA, A CORPORATION OF INDIANA

GUIDE BAR FOR SLICING MACHINES

Application filed February 7, 1929, Serial No. 338,133, and in Great Britain February 2, 1928.

This invention relates to slicing machines of the type in which the substance to be sliced is clamped upon a carriage which is adapted to be moved back and forth past the slicing 5 knife whereby slices are cut therefrom, the carriage being supported by one or more stationary guides mounted upon the base of the machine.

In this type of machine it is desirable to 10 shield the guiding surfaces for the purpose of preventing grease, grit, or other foreign matter, from accumulating thereon to contaminate or roughen said surfaces.

One object of this invention is therefore to 15 provide a covering means for the guiding surfaces to prevent the accumulation of grease, grit, and other foreign matter and this covering means preferably extends above and below said guiding surfaces.

20 Another object of this invention is to provide a lubricating means for the guide rods which will deliver the lubricant to the guide rods in desired quantities. Furthermore, this lubricating means forms part of the covering 25 means for the guide rods in the embodiment shown but may be a separate part thereof without departing from the spirit of the invention.

Another object of this invention is to 30 provide a ring surrounding the guide rod for carrying the lubricant from the trough to the guide rod.

Other objects of the invention will appear 35 hereinafter, the novel features and combinations being set forth in the appended claims.

In the drawing:—

Fig. 1 is an elevational view of the front 40 part of a machine embodying my invention, with parts thereof in section for the sake of clearness; and

Fig. 2 is a side elevation, also partly in section, for the sake of clearness.

The slicing machine in the embodiment 45 shown comprises a base 1 above which there is a carriage 2 carrying bearing members 3 slidable upon rods 4 supported at their ends by upright members 5, fixed to the base. The carriage 2 has the usual cross-feed-carriage 6 adapted to advance the work toward the 50 knife 10, and has uprights 7 supporting a

clamping member 8 adapted to engage and hold the material 9 which is to be sliced, and a handle 8' is used to manipulate the clamp 8. The knife 10 is mounted on a shaft 11' journaled in a bearing 11 fixed to the base 1. 55

In the operation of the machine, the carriage 2 is reciprocated along the rods 4, carrying the material 9 successively past the knife so that slices may be cut therefrom as the material is advanced to the left, as shown in 60 Fig. 1, to position the material so that the next slice may be cut therefrom.

To reciprocate the carriage, a shaft 15 is adapted to be rotated by a handle 7 mounted on the flywheel 16 directly mounted on the 65 shaft 15. The rotation of the shaft 15 rotates the crank 12 by means of beveled gears, not shown, since this construction is well-known. The rotation of crank 12 causes the carriage 2 to be reciprocated on the guides 4 by means 70 of its connection with the carriage comprising a pitman 13 pivotally connected at one end to the bracket 14 integral with one of the bearings 3 and pivotally connected at its other end to the crank 12. 75

More particularly, this invention is concerned with the construction of the guiding means for the carriage and the protecting means and lubricating means therefor. Surrounding each guide rod 4 and spaced therefrom is a tubular member 18 mounted at its ends in brackets 19 fixed to the rods 4 and has a slot 20 extending substantially the length thereof for a purpose presently to be described. 85

Each of the bearing members 3 has a portion extending through the slot 20, which portion has an extension adapted to be fastened to the carriage by any suitable means, such as bolts, but these extensions may be 90 made integral therewith, if desired. The tubular member 18 forms a cover for the guide 4 as well as providing a trough in which a lubricant may be placed for the purpose of lubricating the guide rods 4. 95

On each of the guide rods is placed a ring 21 which encircles the guide rod and extends into the lower part of the tubular member 18 so that as the ring is rotated, it will carry 100 with it small quantities of oil from the trough

and thus lubricate the surface of the guide rod 4 and especially the upper surface where most of the weight of the carriage is received. It is desired to have a means to automatically 5 rotate the ring only a small amount each time that the carriage is reciprocated so that only a small quantity of oil will be added to the surface of the rod. For this purpose, each of the bearing members 3 has a pin 22 extending therefrom towards the ring and spaced from the rod only a small amount so that as the carriage is reciprocated, the pins 22 alternately will engage the inner side of the ring 10 to raise the ring slightly on one side and cause it to rotate slightly about the rod 4. The bearing members 3 also cause the ring to slide along the rod 4 when it is struck by the pin 22. This distributes the lubricant along the rod instead of depositing it all at one 15 place. The operation of this device is as follows:—

As the handle 17 is turned, the carriage is reciprocated upon the guide rods 4 by means of the connections 16, 15, 12, 13 and 14, connecting the handle 17 with the carriage. The carriage is moved past the knife until the slice has been cut from the material thereon after which the carriage returns and the material is advanced toward the knife the thickness 20 of the slice desired to be cut therefrom. Upon each reciprocation of the carriage, one of the pins 22 engages the ring 21 to feed the lubricant to the rod, as previously described, so that the movement of the bearing member 25 3 on the rod 4 is smoother than it would be without the use of a lubricant.

Obviously, it is not necessary to have the covering member mounted on the rod but this may be supported in any manner desired and 30 it may also be desired to dispense with that portion of the tubular member 18 which forms a cover therefor, using only that part which forms a trough for the lubricant. Or it may be desirable to use the cover only as 35 a protecting means for the guide rod. The slot 20 may be positioned at other places about the periphery of the tubular member without departing from the spirit of this invention.

Obviously those skilled in the art may make various changes in the construction and arrangement of parts without departing from the spirit and scope of the invention as defined by the claims hereto appended, and 40 I therefore do not wish to be restricted to the precise construction herein disclosed.

Having thus fully described and shown an embodiment of my invention, what I claim and desire to secure by Letters Patent of the 45 United States is:—

1. In a slicing machine, the combination with a slicing knife, of a support and a table slidably mounted on said support by guiding means comprising a guide on said support 50 and co-operating means on said table, and a

cover extending above and below said guide, said cover also forming a trough for a lubricant which is to be supplied to said guides.

2. A slicing machine comprising a reciprocating carriage and a support therefor, 55 guides on said support, bearing members on said carriage engaging said guides, a cover extending above and below each of said guides, said cover forming a means for holding lubricant to be supplied to the guides, 60 and means for supplying the lubricant in said cover to said guides.

3. A slicing machine comprising a support, a table reciprocable above said support, guiding means between the table and support comprising a guide member and a bearing member slidable on said guide member, one of said members being fixed to said support and the other being fixed to said table, and a cover extending over and under 65 said guide rod, said cover also forming a trough for lubricant to be supplied to said guide member.

4. In a slicing machine, the combination with a slicing knife, of a support, guiding members on said support, bearing members on said guide members, a cover over and under said guide members, said cover also forming a trough for a lubricant, a reciprocating table connected to said bearings and 70 supported thereby, rings surrounding said guiding members and extending into said trough, means on said bearing members for engaging and rotating the rings as the table is reciprocated for supplying lubricant to 75 said guiding members.

5. A slicing machine comprising a reciprocating table, a support, a guide mounted on said support, a tubular cover mounted on said guide and substantially covering the 80 entire guide, said cover having a narrow slot in a vertically arranged face thereof, and a bearing fastened to said table and projecting through said slot into said cover to engage the guide.

6. A slicing machine comprising a reciprocating table, a support, guides mounted on said support, covers substantially enclosing said guides each having a slot therein and being mounted on said guides, bearing 85 members on said table projecting through said slots to engage said guides, lubricating means in said cover, rings surrounding said guides and adapted to extend into said lubricating means, and pins projecting from said bearing members to engage said rings as the table reciprocates to thereby rotate the rings and supply lubricant to the guides.

7. A slicing machine comprising a reciprocating table, a guide, a lubricant trough beneath said guide, a cover extending over said guide and trough but spaced therefrom so as to provide a space between said cover and trough at one side of said guide, a bearing member having a portion thereof arranged 90

between said cover and trough and engaging said guide, said bearing member having a portion thereof projecting through said space between said cover and trough, a table operatively connected to said bearing, a ring surrounding said guide, and means on said bearing for tilting said ring to such a position that its axis is at an angle to the longitudinal axis of said guide to thereby cause said ring to rotate about said guide as said table reciprocates.

8. A slicing machine comprising a reciprocating table, a guide bar, a cover for said guide bar, a trough arranged adjacent said guide bar for receiving a lubricant, said cover protecting the lubricant in said trough, a bearing member engaging said guide bar and operatively connected to said table by means projecting between said cover and said trough, a lubricant ring surrounding said guide bar and freely supported thereby, and means for tilting said ring to various angular positions relatively to said guide bar as said table reciprocates.

25 9. A slicing machine comprising a reciprocating table, guides for guiding the reciprocations of said table, hollow members surrounding said guide throughout substantially the entire length thereof, slots arranged in 30 the sides of said hollow members, and bearing members projecting through said slots and engaging said guides and operatively connected to said table, said hollow members being adapted to receive a lubricant in the 35 bottom portion thereof, said slots being arranged in said hollow members in such positions that foreign material may not readily enter said hollow members and thus contaminate the lubricant or fall upon the upper surfaces of the guides.

40 10. A slicing machine comprising a reciprocating table, guide bars, bearing members connecting said guide bars and table, tubular members surrounding said guide bars 45 and extending substantially throughout the entire operative length thereof, said tubular members having slots in the sides thereof through which said bearing members extend, said tubular members acting as lubricant 50 troughs and as covers for said guides, lubricating rings surrounding said guides and freely supported thereon so that normally they occupy positions such that their axes extend parallel with the axes of the guide bars, 55 and means for tilting said rings to positions in which their axes extend at angles to the axes of said guide bars, said rings being adapted to convey lubricant from said trough to said guide bars.

60 11. A slicing machine comprising a guide bar, a table, a guide member guided by said guide bar and operatively connected to said table, a tubular member surrounding said 65 guide bar throughout substantially the entire operative length thereof, said tubular

member having a longitudinal opening in one side thereof through which said guide member is adapted to extend, projections movable with said table, a ring surrounding said guide bar and having a portion thereof lying between said projections, and means for reciprocating said table along said guide bar to cause said projections to engage said ring and cause said ring to rotate about said guide bar, 70 said tubular member also having a portion 75 thereof acting as a lubricant trough.

12. In a slicing machine, the combination with a guide rod, of a cover encircling said guide rod but spaced therefrom, a slot in said cover, a substance support, a bearing member on said substance support extending through said slot into engagement with said rod, a ring surrounding said rod, and opposed projections on said bearing in a position to engage said ring to tilt said ring about its point of support on said rod as said substance support is reciprocated, and to carry said ring along said rod so that said ring rotates about said rod during reciprocation of said substance support, said cover acting also as a 85 lubricant receptacle and said ring acting as a lubricant distributor to distribute the lubricant in said cover to the surface of said rod as said ring rotates about said rod.

In testimony whereof I have signed my 90 name to this specification on this 21st day of January, A. D. 1929.
